M. JACOBSKY

ELEVATOR DOOR LOCK

Original Filed Feb. 24, 1923

Patented Feb. 17, 1925.

1,526,790

UNITED STATES PATENT OFFICE.

MAXIM JACOBSKY, OF NEW YORK, N. Y.

ELEVATOR-DOOR LOCK.

Original application filed February 24, 1923, Serial No. 620,912. Divided and this application filed October 23, 1923, Serial No. 670,709.

To all whom it may concern:

Be it known that I, MAXIM JACOBSKY, a citizen of Poland, residing at New York, county of New York, and State of New York, have invented certain new and useful Improvements in Elevator-Door Locks, of which the following is a specification.

This invention relates to improvements in locks, particularly locks intended for use with elevator doors as for instance described in my application Serial No. 620,912, filed Feb. 24, 1923, Patent No. 1,476,254 dated December 4, 1923, of which this application is a division, and it is the principal object of my invention to provide a lock of this type which will automatically lock the elevator door in its closed position, thus preventing accidents.

Another object of the invention is to provide a simple elevator door lock which is inexpensive to manufacture, durable, and which can be readily attached to any elevator door now in common use.

A further object of the invention is to provide a lock which is also adapted for use with car doors, as for instance subway cars or the like, in short with doors of all descriptions. *

A still further object of the invention is the provision of a lock allowing an adjustment of the operating parts to suit the varying measurement of the door jambs.

It is also the object of my invention to provide a readily and conveniently operating handle for opening the locked door by an easy manipulation of the handle.

These and other objects of my invention will become more fully known as the description thereof proceeds, and will then be specifically pointed out in the appended claims.

In the accompanying drawings, forming a material part of this disclosure:

Figure 1 is a side elevation of an elevator door lock constructed according to the present invention.

Figure 2 is a similar view of my lock with the cover removed and looking in the direction of arrows 8—8 of Figure 4 with the lock in open position.

Figure 3 is a view similar to Figure 2 with the lock in locking position.

Figure 4 is a longitudinal section through the lock on line 10—10 of Figure 2.

Figure 5 is a top plan view of a locking base plate.

Figure 6 is an end view thereof.

Figure 7 is a top plan view of a locking top plate.

Figure 8 is an end view thereof.

Figure 9 is a cross-section on line 15—15 of Figure 2.

Figure 10 is a section on line 16—16 of Figure 1.

As illustrated the lock comprises a casing 10 adapted to be secured to an elevator door 65 and closed at its front by means of a cover plate 11 adapted to be attached to the casing by means of screws 12, 13, 14, 15 adapted to enter suitable holes in the corner pieces 16, 17, 18, 19 in the casing. 70

The cover plate 11 has a central opening 20 for the reception of the hand of the operator for operating a finger grip or handle 21 pivotally secured at its lower end by means of a screw 22 entering a socket 75 23 in the casing.

Integrally made with the casing is a guide block 24 arranged at the upper end of one of the edges of the casing and recessed as at 25 to guide a locking latch 26 attached to 80 the end of a rod 53 having a central flat part 54 flattened in the opposite direction, while the inner end of rod is screw threaded as at 56 and enters an open channel 57 in corner piece 18 of casing 10. 85

A flat plate 58 is slidably arranged upon the rear wall of the casing, and this plate carries on its upper face an abutment lug 59 in its left hand corner adapted to engage the flattened part 54 of rod 53 at one side, 90 and an abutment lug 60 at some distance from its upper edge and approximately in its center adapted to engage flat part 55 of rod 53 from the opposite side.

The plate 56 has the form illustrated in 95 Figure 5, and carries at its lower right hand corner an upstanding flange 61 and a projecting pin 62, both for a purpose herein-after more fully to be described.

Another plate 63 adapted to rest upon 100 and slide on plate 58 has an upper shoulder 64 bent out of the plane of plate 63 which bears on its lower face a lug 65 near the shoulder 66 on plate 63 in one corner thereof, and an upper lug 67 near the upper edge of shoulder 64 in approximately its center, while an opening 68 is provided in plate 63 near shoulder 66 in approximately its center. Lug 65 is adapted to engage flat 105 part 54 of rod 53 from one side thereof op- 110

posite to the side engaged by lug 59, while lug 67 engages flat part 55 of rod 53 from a side opposite to the side engaged by lug 60. Near its left hand lower corner the 5 plate 63 has a projecting pin 68 in its upper face as shown in Figures 7 and 8.

A rod 69 is slidably and transversely arranged in casing 10 and carries at one of its ends a head 70 adapted to project 10 through one of the edge walls of the casing, while its opposite end slides in a bore of corner piece 16 open at its end.

Intermediary its ends the rod 69 carries two spaced collars 71, 72, and a collar 73 15 is arranged on head 70 within casing 10. A spring 74 is wound around rod 69 between collar 72 and collar 73 and another spring 75 is wound around rod 69 between collar 71 and the inner edge of corner piece 20 16, both springs tend to press head 70 out of casing 10.

A spider 76 is pivotally mounted on a hollow stem 77 projecting from the rear wall of the casing 10. One arm, 78 of the 25 spider 76, has a socket on its lower face adapted to be engaged by pin 62, while the opposite arm 79 of spider 76 has a depending socket on its lower face adapted to be engaged by pin 68. A third arm 80 of the 30 spider is angularly disposed to the other arms and serves a purpose which will later more fully be explained.

A handle plate 81 with an inner depending flange 82 is pivotally resting upon the 35 upper end of stem 77, and a screw 83 is holding the parts together. A lug 84 is attached to the lower face of spider 76 and provided with two depending fingers 85 and 86 adapted to engage rod 69 to both of 40 its sides between collars 71 and 72. A key hole 87 is provided in the front plate through which the bit of a key may be inserted to engage flange 61 if it is desired to operate the lock by a key.

45 The device operates as follows—

If the operator closes the door, the head 70 will engage the keeper in the jamb of the door and will be pressed inwardly against the action of springs 74 and 75.

50 This operation will operate fingers 85 and 86 between collars 71 and 72 and turn the spider 76 to the underside of which the fingers are rigidly fastened.

55 Arm 78 of spider 76 will move upwardly, while arm 79 moves downwardly, and as arm 78 is connected to pin 62 of plate 58 and arm 79 to pin 68 of plate 63, plate 58 will be moved upwardly, while plate 63 will execute a downward movement, and lug 60 of 60 plate 58 will engage the flat portion 55 (Fig. 2) to rotate rod 53 and its latch 26 into locking position indicated in Figure 1. This turning movement of rod 53 will be assisted during the simultaneous downward 65 movement of plate 63 by its lug 67 engag-

ing flat portion 55 from the side opposite to the side engaged by lug 60 as both lugs are in different planes and arranged to act at different times.

If it is desired to open the door, the 70 operator will manipulate the handle 81 by pressing the same towards the right so that its flange 82 will engage arm 80 of spider 76, resulting in a turn of the spider toward the right, so that arm 78 will go down and 75 arm 79 will move upwardly.

Plates 58 and 63 will follow these movements with the result that lug 65 of plate 63 will engage the flat portion 54 of rod 53 from one side, while lug 59 of plate 58 will 80 engage it from the opposite side although in a different plane and the plate movements are so timed that the downward movement of plate 58 and the upward movement of plate 63 will rotate rod 53 and its latch 85 into unlocking position, while springs 74 and 75 will press head 70 out of the casing to be ready for another closing operation.

Also in this case an operation of screw end 56 of rod 53 by means of a suitable 90 tool, will allow an adjustment of the rod to suit various door jambs.

It will be clear that changes may be made in the general arrangement and in the construction of the minor details of my invention without departing from the scope and 95 spirit thereof.

Having thus described my invention, what I claim as new, and desire to secure by Letters Patent of the United States is:

1. A lock comprising a rotating locking member, a pair of superposed sliding plates, lugs on said plates adapted to engage said locking member to rotate the same into and out of its locking position, means for sliding said plates in opposite directions, a contact member adapted to operate said means to actuate said plates to turn said locking member into locking position, a handle for operating said plate sliding means to operate the plates to turn said locking member into its normal unlocking position, and means for allowing an adjustment of said locking member to suit various door jamb constructions.

2. A lock comprising a rotatably arranged locking member, two flattened parts on said member, a pair of sliding plates, one under and the other above said member, lugs on the opposite inner faces of said plates so arranged to engage opposite faces of said flattened parts to engage the same upon the movements of said plates in opposite directions for turning said locking member into and out of its locking position, a rotatably arranged spider, arms on said spider connected to said plates to actuate the same upon the actuation of said spider, a contact rod adapted to actuate said spider to operate said plates and lugs thereon to rotate 125 130 135

5 said locking member into locking position upon the actuation of said contact rod, another arm on said spider, a handle, a flange on said handle edge to engage said last
10 named spider arm for operating said spider and plates connected therewith to move the lugs thereon to rotate the locking member into its normal unlocking position, and means for allowing an adjustment of said 15 locking member to suit various door jamb constructions.

15 3. A lock comprising a casing, a locking member rotatably arranged in said casing transversely thereto, a latch head on said member projecting from said casing, means for varying the degree of projection to suit the varying door jamb construction, a spring controlled contact member having a contact head projecting from said casing, collars on 20 said rod, a spider, means on said spider to engage said collars to both sides of said rod for allowing an operation of said spider upon the engagement of said contact head by a door jamb, a means operated by said 25 spider for rotating said locking member into and out of its locking position, and a hand operated handle for operating said spider to actuate said locking member rotat- 30 ing means to turn said latch head into its normal unlocking position.

4. A lock of the class described comprising a casing, a removable cover for said casing having a central opening, a hollow stem provided with an inner thread projecting from the rear wall of said casing through 35 said cover, a spider rotatably secured to said stem, a flanged handle upon the extreme outer end of said stem, a screw engaged in said stem for keeping the parts together, two oppositely disposed arms on said spider, a 40 pair of superposed sliding plates, projecting pins on said plates adapted to engage in sockets of said arms for sliding said plates in opposite directions, a third arm on said spider adapted to be engaged by the flange 45 of said handle, a rotatable locking member, means on said plates adapted to engage said locking member to rotate the same upon the operation of said plates by said spider in and out of its locking position, an upstand- 50 ing flange on one of said plates, depending lugs on said spider, a contact means adapted to engage said depending lugs for turning said spider into locking position when said contact member engages a door jamb and into unlocking position when said spider is 55 operated by said handle.

In testimony whereof I have affixed my signature.

MAXIM JACOBSKY.
